UNITED STATES PATENT OFFICE.

AUDLEY E. HARNSBERGER, OF STAUNTON, VIRGINIA.

TYPE-WRITING MACHINE.

SPECIFICATION forming part of Letters Patent No. 447,773, dated March 10, 1891.

Application filed October 23, 1889. Serial No. 327,954. (No model.)

To all whom it may concern:

Be it known that I, AUDLEY E. HARNSBERGER, residing at Staunton, in the county of Augusta and State of Virginia, have invented 5 certain new and useful Improvements in Type-Writing Machines, of which the following is a specification.

My invention relates to that class of writing-machines in which a type-wheel is employed which is connected with a rotary shaft operated by a suitable lever or levers.

My invention has for its object to provide a machine of this character in which a type-wheel is loosely mounted on a supporting-shaft, which is operated by suitable intermediate gears engaging said wheel and a rock-shaft suitably mounted in the frame of the machine, said shaft being operated by a series of key-levers arranged to extend to the 20 front of the machine and arranged as a key-board, in a manner similar to the key-boards of machines now in use.

It has also for its object to provide for suitable connections between said lever and the 25 rock-shaft, whereby an approximately equal depression of the type-keys will tend to rotate the said shaft to different degrees, whereby the type-wheel will be moved so as to bring the desired letter or character in position for printing, in a manner hereinafter 30 fully set forth.

It has also for its object to provide a machine which in form will be compact but yet of such a size as to conveniently admit of a 35 double set of key-levers and two type-wheels which operate independent of each other but in a similar manner, one of said wheels operating to print the letters and characters, while the other wheel is provided with a type-surface formed of twenty-six (more or less) of the 40 most prominent words used—*e. g.*, “the,” “and,” “can,” “have,” “for,” &c.

Finally, my invention has for its object to provide a machine which may be easy to manipulate, which can be constructed at a cost 45 much less than that of the machines now most commonly used, which presents a key-board easily comprehended and simple in arrangement, and which will act to operate the 50 type-wheels and spacing devices in a simple and effective manner.

To this end my invention consists in sundry novel combinations and peculiar arrangement of parts, all of which will hereinafter be fully described in the annexed specification 55 and particularly pointed out in the claims, reference being had to the accompanying drawings, in which—

Figure 1 is a plan view of my improved writing-machine. Fig. 2 is a vertical transverse section of the same, taken on the line 2 2, Fig. 1, looking in the direction of the arrow. Fig. 3 is a detail plan view of the central portion of the machine, showing more clearly the arrangement of the type-wheels, 65 type-levers, rotary shaft, and the adjacent parts. Fig. 4 is a detail view illustrating the pivotal arrangement of the last type-lever and its connection with the rotary shaft. Fig. 5 is a similar view of the first type-lever and 70 its connection with the rotary shaft. Figs. 6, 7, 8, and 9 are detail views illustrating the mechanism for operating the carriage-mover or spacer-wheel and the ribbon-shaft, all of which will hereinafter be specifically referred 75 to. Fig. 10 is a detail view of the bed or paper-supporting plate. Figs. 11, 12, and 13 are detail views of the tripping mechanism for operating the impression-bar, which will be hereinafter specifically referred to. Fig. 14 is a detail cross-section of the type-wheels and their supporting-shaft, taken on the line 14 14, Fig. 3. Fig. 15 is a detail perspective view of the carriage-frame. Fig. 16 is an inverted plan view of the bed-plate with the detachable 85 inking-rollers in position, and Figs. 17, 18, and 19 are detail views hereinafter referred to.

Referring to the accompanying drawings, the letter A indicates a suitably-constructed 90 frame or casing, the front or key-board portion of which is covered, as at a, while the rear portion is open at the top, as shown, but closed at the bottom, as at a', to form a support for the type-wheels and bed-plate. In 95 the vertical standards a² a², secured to the bottom a', I support a fixed-shaft B, formed of two sections b b', as most clearly shown in Fig. 14 of the drawings. Upon the section b is loosely mounted the word type-wheel C, 100 while the letter and character wheel D is supported to slide laterally on the adjacent ends

of the sections b b' , as shown, the object of having a lateral movement for the letter and character wheel appearing farther on.

The wheels C and D are each provided on their periphery, preferably upon the upper rear face, with a lateral flanged portion C' D', upon which are secured segmental type-sections C² D², as shown. The word-wheel type-section is provided with a series of equidistantly arranged words, preferably twenty-six of the words most commonly used, such as "the," "and," "have," "them," &c., such words being of not more than four letters. The type-section D² is provided with a series of letters and characters, which are arranged in the same longitudinal alignment with the words on the word-wheel, said letters and characters being arranged in the manner most clearly shown in Fig. 3, from which it will be seen that I arrange the series in parallel rows, with the capitals adjacent the word-wheel, the small letters next the capitals, and the characters and numerals next the small letters.

As before stated, I arrange the type-wheel D so it can be moved laterally. The object of this is to bring either of the circumferential rows of letters or characters in line with the impression-opening X in the bed-plate of the machine. To this end I provide the wheel D with hub portion d, provided with an extension, as d', the hub portion proper fitting on the end of the shaft-section b, while the extension d' is supported on the shaft-section b', as shown.

It will be seen by reference to Fig. 14 of the drawings that the distance between the wheel D and the support a² is such as to admit of the wheel D being moved toward the wheel C a distance equal to the distance between the row of capital letters and the characters, thus admitting of either of the circumferential row of letters or the characters being brought in alignment with the opening X.

To provide a simple means for operating the wheel to shift the same as occasion may require, I arrange a shifting-lever E, pivoted at e to the rear wall a³ of the case to swing horizontally, and provide same with a collar portion e', provided with elongated slots e² e² to receive projecting studs d² d², projecting from the hub portion d'.

The forward end of the lever E extends through the slot 1 in the front wall a of the machine and is provided with a spring-stop E', secured upon its upper face, its end having a suitable knob e³, upon which for convenience the word "Shifter" may be printed or impressed. The slot 1 is formed with notches 2 3 4, into any one of which the spring-stop may be held when the shifter is adjusted as desired. It will thus be seen by reference to Fig. 17 that should the capitals be in position for printing the stop E' would engage the notch 2, and when the small letters are in position it would engage the notch 3.

3, and when the characters are in position it would engage the notch 4.

As before stated, I arrange the type-segments upon the upper rear faces of the wheels C D, said segments extending preferably about one-third the circumference of said wheel.

It will be observed by reference to Fig. 2 that the twenty-six words or letters are disposed equidistantly apart, and that to bring the upper or first letter or word into position beneath the opening X the minimum rotation of the wheel will be necessary, while the maximum movement of the wheel will be required if the last word or letter is moved in position beneath the opening X, said movement being twenty-six times the distance of the first movement.

As the means employed for obtaining the movement of the word-wheel are the same as that for the letter-wheel, I shall describe the means for moving the letter-wheel and shall apply the letters of reference used in designating said means to the similar parts for operating the word-wheel in the drawings. As before stated, I rotate said type-wheel C to the various movements necessary by means of a rotatable shaft operated by a series of key-levers having approximately the same movement of depression. For this purpose I employ a rock-shaft F, journaled at its inner end in a standard f, its outer end being journaled at f' in the casing, as shown in Fig. 1 of the drawings. In practical construction I shall connect said shaft with the key-levers G by means of the movable arms H, loosely journaled on the shaft F, and connect said arms H with the levers G by the connecting-rods I in such a manner that the greatest movement of said shaft will be but about one fifth of a revolution, the differences between the movement of each key-lever and its adjacent lever being of a degree equal to one twenty-sixth of the one-fifth movement of the shaft F.

Figs. 4 and 5 of the drawings represent diagrams illustrating the manner in which the key-levers communicate the desired movement to the shaft F. For illustration I have shown the first key-lever and the last key-lever, the comparative relation of the series of levers being most clearly shown in Fig. 1 of the drawings.

In Fig. 5 it will be seen that the arm H, which is loosely journaled at its rear end on the shaft F, has its front end extended some distance forward, while in Fig. 4 the said arm is very short, and in Fig. 1 it will be seen that the remaining arms successively decrease in length from the first to the last arm, said variations of length being so regulated as to cause the second arm to move two degrees of movement, the fifth five, and the twenty-fifth twenty-five degrees.

Between each of the arms H, I provide the shaft F with a series of projections arranged

in different planes on the front face of the shaft, said projections being so disposed on the shaft to project therefrom at twenty-six different radii, said radii being embraced in 5 about one-fifth of the circumference of said shaft. I prefer to construct said projections by providing a series of collars J, one next each arm H, fixedly secured to the shaft F, the forward peripheral faces of which are 10 provided with projections J', said projections being arranged to project from the shaft in the manner heretofore described.

By reference to Figs. 4 and 5 the construction and operation of the lever-connections 15 between the key-levers and the shaft F will be readily understood. The first key-lever G, Fig. 5, which is journaled on the shaft K, (upon which all the key-levers are journaled,) is provided with a short rear arm or extension G', connected with the forward end of the longest arm H, the rear end of which is provided with a lateral lug h, which engages the projecting lip j on the collar J.

In Fig. 5 I have illustrated by dotted lines 25 the various radii on which the series of projections j are disposed. It will be seen that the projection j, which the first arm H engages, is on radius No. 1. Now when the key-lever G, connected to said arm, is depressed 30 the projection h will engage projection j and move it up to the dotted radius marked o, thus rotating the shaft one degree of its entire movement, which entire movement, as before stated, is but one-third of a complete 35 revolution. Now should the fifth lever be depressed its connection with the shaft is such that the lug h on its respective arm H, which is arranged to be in contact with the projection j on the adjacent collar J, said projection being on radius No. 5, will rotate said 40 shaft until the projection j reaches radius o, and thus rotate the shaft five degrees of its entire movement.

It will be seen (referring to Fig. 4) that the 45 last key-lever G has its extension G' extended a considerable distance to the rear, being connected to the shortest arm H, thereby affording the maximum movement to the shaft when the lever G is depressed—i. e., the projection j is on radius No. 26, and when lever G is operated it is moved to radius marked o, thereby rotating the shaft the entire twenty-six degrees, the varied movements of said shaft being communicated to the type-wheel 50 in a manner presently explained. As before stated, all of aforesaid movements of the shaft are accomplished by approximately the same movement of depression on the key-levers. The depression would be of exactly 55 the same degree were all the finger-pieces of the levers in the same plane.

I find that for practical purposes it is very desirable to have a key-board where the keys are arranged in steps and in a compact form. 60 To this end I arrange my keys in a series of three steps, every third key being a long key, the second an intermediate, and the third a

short key. To admit of this construction of key-board and yet obtain the same movement of the rear ends of the key-levers, I arrange a 70 longitudinal abutting-board L, disposed below the forward ends of the key-levers, and incline the same on plane extending from a point indicated by the lowest movement of the bottom of the longest key-lever and parallel with its lower edge when in its depressed position, as clearly shown in Figs. 4 and 5. By this arrangement I get the proper throw to the rear end of the several levers, although the upper and middle rows of keys 80 are not depressed quite as far as the lower-most rows of keys.

Upon the inner end of the shaft F is mounted to turn therewith a wheel or segment M, provided on its lower front peripheral face with a series of cog-teeth m, extending over about one-fifth of the periphery, the first tooth m' of which normally engages the teeth n' of a series of teeth n, formed on the periphery of a disk N, secured upon the type-wheel D, as shown.

It will be understood that the teeth m and n are of the same size and that the disk N is of such a size that the said teeth n extend over one-third the peripheral face of said 95 disk if the type-section extends the same distance on the type-wheel periphery. This construction is essential, so that a maximum movement of the wheel M will turn the disk N and the type-wheel its greatest throw. It 100 will thus be seen that should the shaft F be turned by means of the proper key-lever to five degrees of its movement it would, through its wheel M and the disk N, turn the type-wheel until the fifth letter on the wheel 105 would be in proper position beneath the opening X in the bed-plate. It will also be observed that by this construction the type-wheel will be turned so as to bring the last letter or any of the intermediate letters into 110 proper position in the same time it takes to move the first letter into position.

To prevent the type-wheel being thrown too far forward at each depression of the type-levers, I employ a stop-pawl P, which operates to enter any of a series of notches c⁵, 115 formed on the front peripheral face of the type-wheel D. These notches are twenty-six in number and are arranged one for each letter and at the same distance apart as said 120 letters.

The pawl P is operated so as to enter the proper notch to hold the wheel from further forward movement when the desired letter is under the opening X in the bed-plate—as, 125 for instance, should the fifth key-lever be operated the wheel will be turned to bring the fifth letter into position and the pawl P will enter the fifth notch c⁵ and hold the wheel from further forward movement.

The pawl P is so adjusted that its movement for engagement with the notches occupies the same time that it takes to move the wheel forward the desired distance—i. e., the 130

time of the movement of the wheel being the same if either the first or last letter is turned in place—and that the time of movement of the pawl is always the same, so the wheel will be turned with the proper notch in position before the pawl will engage same.

In the practical construction I form the pawl of a spring-actuated arm pivoted at p to a vertical standard Q and provide the lower end with a cross-piece p' of a width sufficient to engage either of the type-wheels. To form a convenient means for operating said pawl and to obtain the same movement therefor from all of the key-levers, I provide the same with a forwardly-extending arm P' , to which is pivoted the lower end of a connecting-rod R , the upper end of which is pivotally connected to the rearwardly-extending arm s of a collar S , fixedly secured upon a longitudinal shaft T , journaled in and extending across the machine, as shown. Upon this shaft are loosely journaled a series of forwardly-extending arms U , (one for each key-lever,) of equal length, to the outer ends of which are secured the upper ends of connecting-rods V , the lower ends of which are connected to the key-levers G , as shown. Between each of the arms U is fixedly secured upon the shaft T a series of washers W , provided with projecting lugs w , which engage lateral projections u upon the arms U , as clearly shown in Fig. 13 of the drawings. By this construction it will be seen that if any one of the key-levers G is operated it will raise the arm U upward and cause its lug u to engage the washer W and cause it to partially rotate the shaft T , which in its movement will cause the arm s to depress the end P' of the pawl P and raise its lower end p into engagement with the type-wheel, for a purpose before stated.

Y indicates the carriage-frame, (shown in detail in Fig. 15,) which consists of a rectangular frame provided on its front bar with a spacing rack-bar y , a pointer y' , and a lifter-piece y^2 , while its end pieces are provided with extensions y^3 , to which are secured the travelers or rollers $y^4 y^4$. When adjusted in operative position, the rollers $y^4 y^4$ are supported on a track-bar Z , secured across the rear part of the machine, as most clearly shown in Fig. 2 of the drawings, while its front portion is supported upon a toothed wheel 10, mounted upon a shaft 11, and a roller 12, journaled on a shaft 13, its pointer y' traversing the front edge a^6 of the casing when said edge is provided with the usual space-scale.

The toothed wheel 10, which I will term the "spacer-wheel," is provided with any desired number of teeth, depending upon the length of the line of print for which the machine may be constructed. The shaft 11, upon which said wheel is journaled to turn therewith, is mounted in standards 14 14, secured to the base, the upper ends of which, in connection with standards 15 15, form the sup-

ports for the bed-plate X' , hereinafter referred to.

Upon the shafts 11 and 13, between the standards 14 15, are fixed the ribbon-spools 16 16^a, upon which the ribbon 17 is wound, the ends thereof being connected to said spools in the usual manner, said ribbon being passed between the type-wheels and the bed-plate, as clearly shown in Fig. 2 of the drawings.

To obtain a continuous movement in one direction of the spacer-wheel from the partial movements of the shaft T , I employ the construction most clearly illustrated in Figs. 6, 7, 8, and 9 of the drawings, by reference to which it will be seen that near the end of the shaft 11 I fixedly secure a ratchet-wheel 18, which is engaged by a spring-pawl 19, secured upon a hub 20, loosely mounted upon the end of said shaft, and which is provided with a bevel-gear 21, which meshes with a bevel-gear 22, secured upon the shaft T . The relation of the gears 21 and 22 is such that each partial rotation of the shaft T will cause the pawl 19 to turn the shaft 10, so as to move the spacer-wheel one tooth, and thereby feed the carriage one space, and as the shaft T resumes its normal position it will carry the loose hub 20 and pawl 19 back to their normal position. The pawl 19 is provided with an extension or handle portion 23, so it may be lifted from the wheel 18 when it is desired to wind up the ribbon on the spool 16^a after it has been wound up on the spool 16, the shaft 13 being provided with a suitable crank-handle 24, extended to without the front of the machine, as shown in Fig. 2.

The bed-plate X' , before referred to, which is shown in detail in Figs. 10 and 16, consists of a sheet-metal plate secured upon the upper ends of the standards 14 15, the front and rear ends being curved down, as shown, to admit of the easy movement of the paper. The central portion of the plate X' is cut out, as at x , said portion being covered by a flexible material, such as elastic cloth 25, provided with the opening X for the letter or characters and an elongated opening X^2 , arranged in the same alignment, which forms the impression-opening for the word-wheel.

Should a letter, as "B," follow the word "them," the capital letters being in line for operation, it would be about two spaces away from the preceding word, thereby making the operation of the spacer at this time unnecessary.

In the practical arrangement of my machine I construct it with detachable inking-rollers 30 of usual construction, which are journaled to the bed-plate X' below the outer ends thereof, as clearly shown in Fig. 16. To admit of the ready detachment of said rollers, I provide brackets 31 31, in which are journaled the ends 32 of the roller-shafts, the opposite ends 33 being bent to form eyes 34, through which the securing-screws 35 are

passed. When the inking-rollers are employed, the inking-ribbon is removed.

36 denotes the impression-arm, which is most clearly illustrated in Figs. 1 and 2 of the drawings, and which consists of a horizontal portion 37, extended transversely over the central portion of the machine, which is provided with a rearwardly and downwardly extended portion 38, secured to a short rocking-shaft 39, journaled to the rear wall of the casing, as shown. It is also formed with a depending arm 40, having lateral wings 41, which extend over the openings X X², being normally held just out of contact with the type-wheel. 10 The outer end of the arm 36 extends through a keeper 42, secured upon the upper end of the standard, the lower portion of said keeper being formed by a transverse bar 43, which is formed with an extended portion 44, for a 15 purpose presently explained. The end of the arm is normally held from its rest on the bar 43 by the spring 45, (see Fig. 12,) one end of which is secured to the upper end of the standard, while its lower end is connected to 20 a swinging arm 46, pivoted at its rear end to the inner rear end of the extension 44.

To the outer end of the arm 36 I pivotally secure the upper end of a rod 46, the lower end of which extends within the casing and 30 is connected to a rearward extension 47 of a disk 48, fixedly secured upon the shaft T. By this construction it will be observed that where any one of the key-levers is depressed at the moment the type-wheel is 35 brought into the desired position the disk 48 will be moved by the shaft T, and the rod 46 will force the end of the arm 36 down and cause its winged portion 41 to press the paper against the type, and thereby cause an impression 40 thereof on the paper.

When I employ the inked ribbon, I dispense with the inking-rollers and the direct connection between the arm 36 and the shaft T and make an indirect connection therewith, 45 as most clearly shown in Figs. 11 and 12 of the drawings. In this instance I employ a tilting arm 49, pivoted to the outer rear end of the extension 44, and connect the rear end 50 of said arm to the shaft T by means of a rod 51, connected to the projection 52 of the disk 53, secured to the shaft T, as clearly shown in Fig. 3. In the forward end of the arm 49 I pivot a gravity-tripper 54, which normally engages the lower edge of the outer 55 end of the arm 36.

By the aforesaid construction it will be seen that when the keys are operated, as before stated, the shaft T will cause the rod 51 to throw the front end of the arm 49 upward. The 60 tripper 54, raising the arm 36 and slipping the same, allows it (the arm 36) to fall by gravity, its weight slightly overcoming the tension of the spring 45, and cause its wings to make the impression on the paper by pressing the 65 same against the type-wheel.

It will be understood that the portion of the bed-plate which has the impression-openings

X X², being flexible, permits of the pressure of the wings 38 against the type, as described.

The paper-feeding devices, which are clearly 70 illustrated in Figs. 1 and 2, consist of upwardly-extending arms 55, in which are journaled one above the other the elastic-covered rollers 56 56, which have a frictional bearing with each other. The shaft 56^a of one of the 75 rollers 56 is extended and provided with a ratchet-wheel 57, which is engaged by a pawl 58, operated by pivoted arm 59, to the rear end of which the pawl 58 is pivoted in the ordinary manner, said arm having a handle extending to within convenient reach of the operator. Secured upon the front edges of the arms 55 is a guide-plate 59^a, which extends entirely across the carriage, as shown, the forward end of which extends over the bed-plate 85 near the rear wall of the openings X X² to hold the paper in proper position over said openings. To the rear edge of the standard I secure a curved paper-guide 60, which serves to roll up the paper as it is fed from the feed-rollers and hold same from coming in contact 90 with carriage-supports.

In the front portion of the machine, below the spacer-wheel, I journal a rock-shaft 61, which I term the "spacer-shaft," to which I 95 fixedly connect two key-levers 62 63, one of which I term the "word-spacer" and the other the "letter-spacer." Upon the spacer-shaft I secure one end of a rearwardly-extending arm 64, provided with an upwardly-extending 100 slightly-flexible finger 65, which is guided in a suitable keeper 66, as most clearly illustrated in Fig. 7 of the drawings. The upper end of the finger 65 is provided with a seat 68, in which normally rests one of a series of rearwardly-projecting teeth 69, arranged in a circle near the rear peripheral face of the spacer-wheel, said teeth being of the same number as the notches in the periphery of the spacer-wheel and indicating a distance of one space 105 between each tooth. To normally hold the finger 65 in its proper position, I employ a spring 70, as shown in Fig. 7, the upper end of which moves in an elongated slot 71 of the keeper. 115

It will be understood that when it is desired to print a word such as "you" or "them," moving the carriage and paper a single space will not bring the paper in the proper position, and that the carriage would have to be 120 moved a distance of at least six or seven spaces. For this purpose I arrange the word-spacer in such a manner that in case the word "them" should follow the word "you" by depressing the word-spacer the carriage and 125 paper will be moved forward the desired distance. Should, however, the words "for" or "them" follow the word "it," the operator moves the carriage two or three spaces with the letter-spacer, and then by depressing the 130 word-spacer one time will bring the carriage and the paper in the proper position.

To regulate the movement of the spacer-keys, I arrange them to strike an abutment which

consists of a plate or bar 72, provided with depressed portions 73 74, the portion 73 being so disposed below the letter-spacing key to admit of said key turning the spacer-shaft to move the spacer-wheel one tooth, while the depression 74, which forms the abutment for the word-spacing lever, will admit of said lever turning the shaft to operate the spacer-wheel four spaces.

10 By reference to Fig. 1 it will be observed that I arrange the spacer-keys and the shifting-lever centrally of the key-board and above the other keys, so as to make their arrangement conspicuous.

15 By arranging the letter and character wheel in the manner before described and employing a shifter, as stated, I am enabled to use on one type-wheel three kinds of letters or characters and operate same by one set of 20 key-levers, the arrangement of such letters and characters being clearly understood by reference to the drawings. It will also be understood that any well-known mechanism may be employed to bring the type-wheels 25 back to their normal positions; but I prefer to make the shafts F, which operate said wheel, spring-actuated by employing a volute spring 80, as shown in Fig. 10.

From the foregoing description, taken in 30 connection with the drawings, the general operation and the advantages of my improved writing-machine will readily appear without further description here.

Having thus described my invention, what I 35 claim, and desire to secure by Letters Patent, is—

1. The combination, with the type-wheel journaled in the frame A, provided with a series of types on a segment of its peripheral 40 surface and with a series of peripheral notches arranged in the same relation as the types and disposed on the diametrically-opposite face of said wheel, of a partially-rotatable shaft, intermediate gear-connections between said 45 shaft and the type-wheel, the key-levers, the variable connections between said levers and the rotatable shaft, a swinging detent, and intermediate connections between said detent and the key-levers, whereby said detent will 50 be brought into engagement with any predetermined notch in the type-wheel to limit the forward throw of such wheel, said detent, rotatable shaft, and type-wheel being all operated by a single movement of the key-levers 55 to act substantially in the manner and for the purposes described.

2. In a writing-machine, a type-wheel provided on one segment of its surface with types, a series of notches formed in an approximately diametrically-opposite segment of such wheel corresponding in number and relation with the said types, a rock-shaft journaled independent of said wheel, intermediate gearing between said shaft and wheel, key-levers 60 for rocking said shaft through different degrees of movement, and a pawl or detent 65

adapted to engage any of the notches in the type-wheel to limit the forward rotation of said wheel, said pawl connected with and operated by the movement of any of the key-levers, substantially as and for the purpose described. 70

3. In a writing-machine, a word type-wheel and a letter type-wheel provided on a segment of their surface with types and with 75 notches on another segment thereof corresponding in number and relation with said types, rock-shafts, intermediate gearing between said shafts and type-wheels, said type-wheels journaled independently of each other, 80 key-levers, by which to rock either of said shafts through different portions of its movement, and a pawl or detent adapted to engage any of the notches in either of said type-wheels, said pawl connected with and operated by the key-levers, substantially as and for the purpose described. 85

4. The combination, with the partially-rotatable type-wheel, the rock-shaft F, and the intermediate gearing between said shaft and 90 type-wheel, of the key-levers arranged in banks and the intermediate connections between said levers and shaft, said connections consisting of a series of arms journaled on and projected from said rock-shaft F, said arms having 95 pivotal connections with said key-levers, said pivotal connections arranged at different points forward of the shaft F, whereby the degrees of rotation of said shaft will be varied by the movement of the various key-levers, substantially as and for the purpose described. 100

5. The combination, with a shaft or bearing supported in the frame of the machine and a word type-wheel journaled thereon operating 105 in a fixed vertical plane, of the letter type-wheel journaled on the said support, operating in a vertical plane and adapted for adjustment toward or from the word-wheel, and means for shifting said letter-wheel, substantially as and for the purpose described. 110

6. The combination, with key-levers journaled on a common axis, a rock-shaft T, journaled parallel to said lever-axis, and a connection between said levers and shaft whereby 115 said shaft T is rocked at the movement of any of the key-levers, of a shaft 11, journaled at right angles to the shaft T, a spacer-wheel journaled on said shaft 11 to revolve therewith, a reciprocating carriage operated by 120 said wheel, and a clutch-gear mechanism between said shafts T and 11, whereby a continuous intermittent rotation of the shaft 11 is obtained by the rocking movement of the shaft T, all arranged substantially as and for 125 the purpose described.

7. The combination, with the type-wheels, of the bed-plate provided with the openings X X', the rocking shaft T, connected with and operated by the key-levers, said shaft provided with rearwardly-extending arms, and 130 connections between said arms and the bar

36, whereby said arm is depressed at each movement of the key-levers and shaft T, substantially as and for the purpose described.

8. In a type-writing machine, essentially as described, the combination, with a carriage consisting of a rectangular frame provided with the paper-feed rollers at its rear end and a paper-guide arranged in front of said rollers, of the bed-plate provided with the openings X X² and the curved paper-guide secured to one of the standards of the machine at the front edge of the bed-plate, substantially as shown and described.

9. The combination, with the spacer-wheel provided with fingers extending horizontally from the inner face of said wheel, of a rock-shaft 61, a lifting-finger connected to said shaft, adapted to engage the fingers on the spacer-wheel, and the spacer-levers connected to said rock-shaft, said levers adapted to rock said shaft to different portions of its movement, substantially as shown and described.

10. The combination, with the carriage having a rack-bar, of the shaft 11, spacer-wheel 25, journaled thereon, provided with peripheral cogs or teeth adapted to engage said rack-bar and with lateral fingers of the same number as and arranged in alignment with the said cogs, connections between the said 30 wheel and the key-levers, and an independent rock-shaft having spacing-key levers connected thereto, said shaft connected with the lateral fingers of said spacer-wheel, all arranged whereby said wheel is operated by the 35 movement of the regular key-levers or by the independent spacing-levers, substantially as and for the purpose described.

11. The combination, with the partially-rotatable type-wheel, the rock-shaft connected therewith, as shown, and the key-levers connected with said shaft to operate it, as described, of the impression-bar journaled for vertical movement over said type-wheel, provided with a winged arm disposed normally 45 over said wheel, a standard having a tripping device at its upper end engaging the free end of said impression-bar, and a connection between said tripper and the key-levers, whereby said impression-bar is raised by the tripper and 50 allowed to fall by gravity as the tripper is disengaged from the said bar, all arranged substantially as and for the purpose described.

12. The combination, with the type-wheel, the rock-shaft F, and intermediate gearing

between said shaft and the type-wheel, said 55 rock-shaft provided with a series of projections j, arranged longitudinally thereon and in different vertical planes, of a series of arms H, loosely journaled on said rock-shaft, each provided with a lateral projection h, engaging the adjacent projection j on the shaft F, and a series of key-levers journaled on a common axis, their rear ends connected with the outer ends of the arms H, all arranged substantially as and for the purpose described. 65

13. A type-writing machine comprising a partially-rotatable type-wheel, a rock-shaft geared therewith, a series of type-levers, intermediate connections between said levers and the rock-shaft F, said levers journaled 70 on a common axis, a spacer-wheel mounted on a rotatable shaft journaled in the frame, a carriage engaging said wheel, intermediate mechanism between said spacer-wheel shaft and the key-levers, whereby said shaft is rotated, an impression-bar having a vertical movement over the type-wheel, and intermediate connections between said bar and the key-levers, all arranged whereby the operation of any one of the key-levers will operate 75 the several parts set forth, substantially as and for the purpose described.

14. The combination, with the key-levers journaled on a common shaft, a rock-shaft T, journaled in the frame above said lever-shaft, 85 forwardly-projecting arms loosely journaled thereon, provided with lateral projections adapted to engage radial projections on the rock-shaft T, connecting-arms between said arms and the key-levers, and a bevel-gear 90 mounted on said shaft, of a shaft 13, journaled in the frame at right angles to the rock-shaft, a ribbon-spool mounted thereon, a second shaft 11, parallel to the shaft 13, provided with a ribbon-spool and a roller adapted to support one 95 end of the carriage, said spools carrying the ribbon, a spacer-wheel mounted on the shaft 11, adapted to engage the carriage, a ratchet formed on the shaft, and a clutch-collar engaging said ratchet, having a bevel-gear 100 engaging the bevel-gear on the rock-shaft T, all arranged substantially as and for the purpose described.
